(57) **CLAIM**

The ornamental design for a watch dial as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a watch dial;

FIG. 2 is rear view thereof;

FIG. 3 is a right-side thereof;

FIG. 4 is a left-side thereof;

FIG. 5 is top view thereof.

FIG. 6 is a bottom view thereof; and,

FIG. 7 is a front perspective view thereof.

The features shown in broken lines form no part of the claimed design.

1 Claim, 7 Drawing Sheets
